CLAIM

The ornamental design for a modular computer user interface, as shown.

DESCRIPTION

FIG. 1 illustrates a perspective view of a modular computer user interface.

FIG. 2 is a top view of the modular computer user interface.

FIG. 3 is a bottom view of the modular computer user interface.

FIG. 4 is a front view of the modular computer user interface.

FIG. 5 is a rear view of the modular computer user interface.

FIG. 6 is a left view of the modular computer user interface; and,

FIG. 7 is a right view of the modular computer user interface.

The broken lines immediately adjacent to the shaded top and bottom surfaces define the bounds of the claim which extend to the boundaries but do not include the boundaries; the remaining broken lines on the front surface depict environmental subject matter only and form no part of the claim; all broken lines form no part of the claim.
